UNITED STATES PATENT OFFICE.

JULIUS SIMMONDS, OF UTICA, NEW YORK.

PEDAL ATTACHMENT.

No. 880,585.

Specification of Letters Patent.

Patented March 3, 1908.

Application filed August 16, 1907. Serial No. 388,807.

To all whom it may concern:

Be it known that I, JULIUS SIMMONDS, a citizen of the United States, residing at the city of Utica, in the county of Oneida and State of New York, have invented certain new and useful Improvements in Pedal Attachments, of which the following is a specification, reference being had therein to the accompanying drawing.

My invention relates to an improved pedal attachment for pianos, organs and other instruments provided with pedals, and I declare the following is a full, clear, concise and exact description thereof, sufficient to enable one skilled in the art to make and use the same, reference being had to the accompanying drawings in which like letters refer to like parts throughout.

My invention consists in a device to be used on pianos, organs and other instruments provided with pedals, and its purpose is to provide a simple attachment which can be readily secured to a piano or similar instrument by means of which the opening in the case of the instrument immediately below the pedal may be always closed, at the same time allowing the pedal to be depressed by the foot when operating the instrument, thus preventing the entrance through the said opening of dust, dirt, mice, vermin and any other objectionable things.

Another function of my device is that it acts as an additional spring upon the pedals, raising them back into position when the foot-pressure is removed.

The features of my invention make it possible for the device to be attached to the instrument in a secure manner without upsetting the piano or other instrument and requiring only the removal of a panel or portion of the case at the lower portion of the case of the instrument. The device cannot be displaced by the foot when operating the pedals, is not exposed to view from any point above the pedals, and is adaptable to the usual construction of all pedals on pianos and other similar instruments, as is more fully described hereinafter and specified in the accompanying claims.

In the drawings, Figure 1 is a top view of the bottom of a piano or similar instrument, showing the pedal B, its support D, and the inner end of the attachment as it is secured to the upper side of the piano bottom. Fig. 2 is a vertical transverse sectional view of the lower front part of a piano on the line

x—x in Fig. 1. Figs. 3 and 4 are perspective views of my invention, the latter of a modified form.

Referring to the drawings, A represents the attachment and consists of a flat spring of any suitable material, which bends upward as it extends outward until it comes in contact with the underside of the pedal at or near the outer edge of the opening in the front part of the piano case, where it turns at nearly right angles downwardly and extends far enough to cover the opening in the front of the case.

B represents the pedal of the piano or similar instrument; C represents the opening in the piano case immediately under the pedal and in which the pedal moves up and down; D represents the standards and axle used in the usual method of construction which support the pedal; E and F are screws or tacks or nails by means of which the device A is secured to the upper side of the bottom board G of the piano case.

H is a portion of the front of the case of the piano or similar instrument.

To attach the device A, one removes the front portion H, of the piano, or obtains access to the inside of the case in any other suitable way, the device A is inserted under the pedal and its axle or fulcrum pin and between the standards supporting the same; the flat end a' of the device A is then secured to the bottom board of the piano case, as shown in Figs. 1 and 2, by means of screws, tacks, nails or similar means, so that the end a of the device A will cover the opening C and at the same time pass downward and outside of the front of the case below the opening when the pedal is depressed. In the drawings I show two screws as means for attaching the device, but my invention is not limited to these as either one or more nails, tacks, brads or similar means are just as suitable. For instance, the end of the device may be bent in a prong to be driven into the bottom board, as seen in Fig. 4. It will thus be seen that, when the pedal is depressed, the downwardly extending end a of the device A will pass downward on the outside of the front of the piano case and when the pedal is released by the foot and springs back to its normal position the device A also springs back, remaining in contact with the underside of the pedal and the downwardly extending end a of the device A keeps the opening under the pedal closed.

The device is simple and can be used on pianos and similar instruments of the ordinary arrangement of pedals not only by manufacturers on new pianos, but by any one on 5 pianos already in use.

Having described my invention, what I claim as new and desire to secure by Letters Patent, is:

1. In a piano, a casing, pedals and pedal 10 openings, a guard for closing the opening beneath the pedal, the same consisting of a spring attached at one end to the upper side of the bottom of the case of the instrument and extending outward and upward into contact 15 with the under side of the pedal, the other end extending downward and covering the said opening, substantially as described.
2. In a piano, a casing provided with openings for pedals, and pedals, means for closing 20 the opening below the pedal consisting of a flat spring having one end bent downwardly below the pedal and having one or more apertures in the other end, said end having a prong for holding the spring to the piano 25 bottom, substantially as described.
3. In a piano, the combination with a case and pedals projecting from the case through openings therein, of means for closing the opening beneath the pedals consisting of a

spring bent at one end upward to engage the 30 under-side of the pedal and then downward to close the said opening, the other end being secured to the inner side of the piano case, substantially as described.

4. A guard for closing the pedal-opening in 35 a piano consisting of a spring fastened to the inside of the piano case by prong means bedded in the piano bottom and securing means through the guard near its inner end and at its outer end bearing on the under side 40 of the pedal, the said spring comprising a portion for covering said hole at said outer end of the guard, substantially as described.

5. In a piano having pedals projecting from the case thereof, a member adapted to 45 close the openings in the case when the pedals are elevated, the same consisting of a spring mounted within the piano and extending in a bent extremity into contact with the pedal and thence downwardly in 50 front of and adapted to cover the pedal opening, substantially as described.

In testimony whereof I affix my signature in presence of two witnesses.

JULIUS SIMMONDS.
